Primary Examiner — Abraham Bahta

(74) *Attorney, Agent, or Firm* — McDonald Hopkins LLC

(57) **CLAIM**

The ornamental design for a label sheet with surface texture assembly, as shown and described.

DESCRIPTION

The patent or application file contains at least one drawing executed in color. Copies of this patent or patent application publication with color drawing(s) will be provided by the Office upon request and payment of the necessary fee. FIG. 1 is a perspective view of a first embodiment of a label sheet with surface texture assembly showing our new design;

FIG. 2 is a front view of FIG. 1 thereof;

FIG. 3 is a rear view of FIG. 1 thereof;

FIG. 4 is a first side view of FIG. 1 thereof;

FIG. 5 is a second side view of FIG. 1 thereof;

FIG. 6 is a top view of FIG. 1 thereof; and,

FIG. 7 is a bottom view of FIG. 1 thereof.

The broken lines in the figures are included for the purpose of illustrating portions of a label sheet with surface texture and form no part of the claimed design. Color and texture may or may not form part of the claimed design without departing from the design disclosed. The inventors anticipate that the invention can be any part, portion, element, or combination of elements of the depicted design. The side, top, and bottom views include a shape and appearance that would be evident from the views of the label sheet with surface texture assembly as shown.

1 Claim, 4 Drawing Sheets
(2 of 4 Drawing Sheet(s) Filed in Color)
